UNITED STATES PATENT OFFICE.

BERNARD J. SCHMELZER, OF JOLIET, ILLINOIS.

BUNG.

1,157,906.

Specification of Letters Patent. Patented Oct. 26, 1915.

Application filed November 11, 1913. Serial No. 800,327.

To all whom it may concern:

Be it known that I, BERNARD J. SCHMELZER, a citizen of the United States, residing at Joliet, in the county of Will and State of Illinois, have invented certain new and useful Improvements in Bungs, of which the following is a specification.

This invention relates to improvements in bungs and has for its object to provide a new and improved form of bung which may be readily driven in the bung hole of a beer cask or the like to retain the contents therein under pressure and which may be readily removed therefrom.

Another object is to provide a bung of considerable durability as opposed to the ordinary wooden plug or bung now commonly used.

My invention contemplates the use of a metal retaining member carrying a packing ring preferably of expansive material which will frictionally engage the bung sleeve or lining to prevent leakage therethrough and to retain the bung in position.

Still another object is to provide a bung of the class described which will permit replacement of the expansive ring when the same has become used up. This and other objects will be described and shown in the following specification and accompanying drawings, in which—

Figure 1 is a section through a portion of a barrel and bung hole thereof showing my improved bung in place; Fig. 2 is a perspective of one form of my improved bung; Fig. 3 is a vertical section through the same; Fig. 4 is a horizontal section along the line 4—4 of Fig. 3; Fig. 5 is a side elevation of a form of wrench which may be used with my improved bung.

Like numerals refer to like elements throughout the drawings, in which—

10 designates a cask or barrel provided with a bung hole in which is threaded or otherwise secured a sleeve 11 of suitable material and provided with the tapered inner wall 12, as clearly shown in Fig. 1.

13 designates generally one form of my bung comprising a body portion 14 of metal or the like having the non-circular socket 14^a for engagement by a wrench or the like. This body portion 14 is provided with the depending stud or boss 15 externally threaded, as indicated at 16. The outer periphery 55 of the body member 14 is externally grooved as indicated by numeral 17, this grooved

portion extending from the lower part of body member 14 and terminating short of the top thereof so as to provide a collar portion 18, as clearly shown in Fig. 3. Lugs or 60 small shoulders 19 are formed on the member 14 and extend outwardly from the outer periphery of the groove 17, as shown in Fig. 4. A packing ring 20 is provided with slots or grooves 21 corresponding with lugs 19, 65 and this collar or ring 20 is constructed to fit closely around in the groove 17, the said slots 21 fitting over the lugs 19, thereby serving to prevent relative rotation of the ring 17 and body member 14. This ring is 70 of sufficient thickness to extend slightly beyond the outer periphery of the flange 18 and is preferably constructed of some expansive material such as fabric and rubber, rawhide, rubber, papier mâché or the like. 75 A follower 25, preferably formed of aluminum or other non-contaminating, non-corrosive material is provided, this follower being centrally apertured and threaded, as indicated by numeral 26, to correspond to the 80 threaded boss 15 with which it engages when in assembled relation, as shown in Fig. 3. This follower is provided with the outwardly projecting non-circular head 27 adapted for engagement by a wrench or the like so that it may be attached to or detached from the body member 14. This follower 25 is further provided with the dished-out upper surface 28 surrounded by the peripheral flange 29, this peripheral flange 90 being located slightly outwardly of the outer peripheries of the groove 17, as shown in Fig. 3. A washer or filler 30 is located on the dished-out surface 28 of the follower, the thickness of the same being preferably 95 slightly less than the height of the peripheral flange 29.

It will be apparent that in assembling the device, after the expansive ring 20 has been fitted on the body member 14, the follower 25 carrying the washer 30, may be threaded on the boss 15 and screwed to position wherein the peripheral flange 29 will contact with the ring 20. Further rotation of the follower 25 will force the ring against the collar or flange 18 of the body member 14 and will expand the ring 20 outwardly to increase the external periphery thereof. The bung is then in condition to be utilized and when sealing a barrel may be lightly driven into the sleeve 11, as shown in Fig. 1, in which position it will be retained by the

frictional contact of the packing ring 20 with the tapered inner wall 12 of the sleeve 11. This will insure a tight joint between the bung and the sleeve and not only will 5 serve to retain the bung in place, but will prevent leakage therearound of gas or fluid. The outer peripheries of the follower and body member being less than the inner diameter of the sleeve 11, contact between the 10 said elements is thereby avoided. When it is desired to remove the bung it is merely necessary to insert the head 35 of a wrench or tool 36, and slightly rotate the same, whereupon the bung will become loosened in 15 the sleeve and may be lifted therefrom.

In ordinary practice where wooden plugs are used, for example, and are driven in flush, as is necessary, it is necessary to use an auger or corkscrew or the like to extract 20 them and they readily become broken or split and pieces of the wood fall into the contents of the barrel so that they are troublesome in that respect and also require more time and trouble in their extraction as well 25 as insertion. Should the expansible ring 20 of my device become smooth or worn down so as to prevent a tight fit thereof in the bung hole, the follower 25 may be advanced on the boss 15 to further expand the ring 30 and if such expansion is not sufficient, the follower may be removed and the washer 30 taken out of the same, whereupon further expansion of the ring is possible, as will be 35 apparent from the construction of the follower. Furthermore, when the packing rings become finally worn out they are easily replaced, the metal members being comparatively indestructible and capable of use for a long time.

40 It will be noted that the follower 25 is the only portion of the bung which is in contact with the contents of the barrel and it is preferable to construct this follower of some material such as aluminum which will not 45 taint or contaminate the contents of the cask and which is non-corrosive. I may provide other metal, however, suitably coating or plating the same to accomplish the same object.

50 It is to be noted my improved bung comprises a packing ring of resilient material, the external periphery of which is of greater diameter than that of the adjacent surface of the other bung members, after the whole 55 device is assembled and prior to its insertion in the bung hole of the barrel. This is in contradistinction to devices first placed in the said bung hole and then operated to expand a ring to force it into engagement with the 60 wall of the bung hole. It will be obvious that by the use of my device I may quickly drive the bung in the barrel and treat a num-

ber of barrels in a short period of time, whereas in devices of the character mentioned, a relatively considerable amount of 65 time is required in placing each bung, thereby eliminating them from consideration in practical use.

It will be apparent that while I have described and shown my invention specifically, 70 it will be obvious that the same is susceptible of many modifications, and I do not wish to be restricted to the form shown and described, beyond the scope of the appended 75 claims.

What I claim is:—

1. A bung comprising a body portion having a non-circular socket on one side and a threaded stud on the other side, said body member being further provided with a portion of reduced diameter, a follower having a non-circular boss on one side and a socket threaded for engagement by said stud on the other side, said reduced portion of said body member being provided with lugs or 80 the like, and a packing ring adapted to fit around said reduced portion of said body member and to be maintained in position thereon by said follower, said packing ring being constructed of resilient material and 85 projecting beyond the adjacent surface of said body member and follower, said packing ring being provided with grooves or the like extending over said lugs of said body member whereby relative rotation of the 90 latter with respect to said packing ring will be prevented.

2. A bung comprising a body member having a non-circular socket in one side and a threaded stud on the other side, said body member being further provided with a portion of reduced diameter, a follower having a non-circular boss on one side and a socket threaded for engagement by said stud on the other side, said follower being further provided with a recessed surface adjacent said socket, a peripheral flange surrounding said recess, and a packing ring adapted to fit on said reduced portion of said body member and to be maintained in position by said follower, said packing ring being of resilient material and projecting beyond the adjacent surface of said body portion and follower, said body member being provided with lugs, said packing ring being provided with 100 sockets to fit over said lugs whereby rotation of said packing ring relative to said body portion will be prevented.

In testimony whereof, I have subscribed my name.

BERNARD J. SCHMELZER.

HENRY A. PARKS.

It is hereby certified that in Letters Patent No. 1,157,906, granted October 26, 1915, upon the application of Bernard J. Schmelzer, of Joliet, Illinois, for an improvement in "Bungs," an error appears in the printed specification requiring correction as follows: Page 2, line 113, claim 2, for the word "portion" read *member*; and that the said Letters Patent should be read with this correction therein that the same may conform to the record of the case in the Patent Office.

Signed and sealed this 7th day of December, A. D., 1915.
